UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

PENCIL-SHARPENER.

1,263,738.

Specification of Letters Patent. Patented Apr. 23, 1918.

Application filed October 20, 1915. Serial No. 58,924.

To all whom it may concern:

Be it known that I, JAMES H. BOYE, a citizen of the United States, residing at Chicago, in the county of Cook and State 5 of Illinois, have invented a new and useful Improvement in Pencil-Sharpener, of which the following is a specification.

This invention relates particularly to devices for sharpening lead pencils; and the 10 primary object is to provide a sharpening device for lead pencils which will enable a point of any desired length of lead and any desired degree of sharpness to be obtained with great facility.

15 The invention is illustrated in its preferred embodiment on the accompanying drawing, in which—

Figure 1 represents a perspective view of my improved lead-pencil-sharpener, a pencil undergoing the sharpening operation being shown brokenly; Fig. 2, a perspective view showing the opposite lateral edge of the device; Fig. 3, a perspective view showing the device in open condition; Fig. 4, a view 20 partly in inner plan and partly in section, taken as indicated at line 4—4 on Fig. 3; Fig. 5, a broken sectional view of the wood-paring device employed, shown removed from the casing, or container-holder, and 25 illustrating the manner in which the wood is pared from the lead of the pencil; Fig. 6, a section taken as indicated at line 6, Fig. 4, the lead-sharpening device employed not being sectioned, however; Fig. 7, a 30 section as indicated at line 7, Fig. 4; Fig. 8, a section taken as indicated at line 8 of Fig. 4; Fig. 9, a plan view of the pencil-guide and wood-paring device; and Fig. 10, an end view of the same.

40 The invention, in its preferred embodiment, comprises a container-holder A; a combination pencil-guide and wood-paring device B, located in and carried by said casing; and a lead-abrader, or abrasive lead-sharpening device, C, located in and carried 45 by said casing.

The container-holder A, as the name implies, is adapted to serve as a container-holder for the elements B and C, and also 50 as a container for the wood-parings and lead removed from the pencil in the sharpening operations. The container-holder preferably comprises an open top box 1, and a slightly larger box-form closure or cover 2, 55 which received the box 1 telescopically, the

two members being connected near one end, by pivots 3.

The container-holder is preferably of the rectangular form shown, and may conveniently be made of a length of a couple of 60 inches, and of a width of about an inch and a quarter. The box 1 has upturned narrow flanges, the lateral flanges being provided near the end distant from the pivots 3 with semicircular recesses 1^a.

65 The cover-portion 2 has downturned flanges of somewhat greater depth. The casing may be opened by pressing together the ends of the members 1 and 2 which project back of the pivots 3, thus separating 70 the opposite ends of said members.

The device B comprises a guide-tube 4 having a taper end 4^a; and a fixedly secured wood-paring blade 5 applied to the taper portion 4^a of the guide 4. Thus, the blade 75 5 is inclined, so as to give the desired bevel or taper to the wood as it is pared. The device B is carried by the lateral flanges of the closure 2 of the container-holder, being secured to said flanges by means of 80 clenching lugs 6 (see Fig. 9), which extend through perforations or recesses in the flanges and are clenched or upset so as to provide firm connection with the flanges. At the large end of the tube 4, the lateral 85 flange of the closure 2 is provided with a perforation 7 of large enough diameter to accommodate a pencil. At the taper end of the tube, the corresponding flange of the closure 2 is provided with a relatively small 90 perforation 8 of sufficient size to permit the lead to protrude freely from the casing.

95 The extremity of the cutting edge of the blade 5 which is located at the small end of the tube 4, is indicated at 5^a, and is separated from the axis a, a, of the guide by a space sufficient to preserve the lead when the wood-paring operation is performed. This will be understood from Fig. 7; and the manner in which the lead is 100 preserved and allowed to protrude through the small opening 8, will be understood from Fig. 1, where a pencil D is shown in process of having the wood pared. The taper portion of the guide-tube is provided adjacent 105 the knife with a slot 9 through which the shavings pass, as they are formed. The slot 9 is disposed at the lower side of the guide so that the parings will drop into the box 1. It will be understood that in Fig. 6, 110

the container-holder is shown inverted. In practice, the knife is located a sufficient distance from the bottom of the box 1 to enable the parings to drop into the box. When 5 the container is closed, the semi-circular recesses 1^a embrace the guide-tube 4. The taper end of the tube 4 (see Fig. 10) has an inner arc-form wall 9^a, conforming to the lead of the pencil. The wall is recessed, 10 grooved, or cut away, as indicated at 9^b, to afford clearance back of the knife, so that any shavings which may chance to be drawn into the guide (slipping between the knife-edge and the taper-portion of the pencil) 15 will be afforded egress through the recess 9^b and casing-opening 8.

The lead-pointing device C, in the form illustrated, comprises a pair of file-toothed, spring-held, jaws 10 and 11 which are disposed beneath or suspended from the top 20 wall of the casing-member 2. The file-members 10 and 11 have curved shank portions securely fastened to the spring arms of a member 12 which has an attaching portion 25 13 secured to the top wall of the casing-member 2, as by rivets 13^a. The spring-arms and the clip may be integrally formed. The file-members 10 and 11 are made concavo-convex, with their convex portions opposed to each other and the extremities separated, to afford between them a space 14 which registers with a hollow tapering 30 guide-member 15 carried by one of the lateral flanges of the cover 2. The corresponding flange of the box 1 is recessed to accommodate the guide-member 15. After the pencil D has been inserted in the guide B and turned therein to pare away the wood and leave the lead *d* projecting through the 35 small opening 8, the pencil is withdrawn from the device B and the lead is then inserted through the guide 15, and the lead is pointed by a reciprocating motion thereof between the spring-held file-members 10 and 40 11. The divergent end-portions of the file-members are preferably smooth and the pointing of the lead is effected between the roughened convex portions. By the use of opposed, spring-held file-members it is possible 45 to secure a rapid sharpening operation by a simple longitudinal reciprocation of the pencil, accompanied by occasional slight rotary oscillation.

The fine shavings, or wood-parings, and 55 the particles of lead removed by abrasion are received in the same chamber. In practice, the lead particles are sifted through and mixed with the parings, and there is sufficient affinity between the wood and lead 60 particles to prevent the lead filings from sifting out through the openings of the casing.

On occasion, when it may be necessary, the container may be opened by pressing together 65 the rear end of the box-form mem-

bers comprising the casing, thus permitting the contents to be dropped into a waste basket. The device may be freely handled, and the pencil-sharpening operation may be performed without soiling the hands.

70

A device of the character described may be manufactured cheaply and sold at a popular price. Such a device may sell at the price of ten cents for instance, is highly satisfactory and fairly effective for the purpose intended, enabling even better results to be obtained than can be secured by the use of pencil-sharpening devices now on the market costing several dollars.

75

The feature of substantially preserving the lead in the wood-paring operation and performing the lead-pointing operation separately is an important one, as it enables the best results to be secured. Moreover, the feature of permitting the lead to protrude through the side of the container-holder enables the length of the lead point to be gaged accurately and avoids unnecessary waste. As is well known, in machines in common use a very great waste of the pencil occurs through the inability of the operator to observe the result of the sharpening operation, and because of the fact also that where the cutter operates directly on the lead, the lead is frequently broken over and over again before a satisfactory point is obtained.

90

Changes in the form, disposition, etc., of the elements are contemplated; hence no unnecessary limitation is to be understood from the foregoing detailed description, which has been given for clearness of understanding only, but the appended claims should be construed as broadly as permissible in view of the prior art.

100

What I regard as new and desire to secure by Letters Patent is:

1. In a lead-pencil sharpener, the combination of a container-holder and a pencil-guide therein having a taper portion equipped with a knife so disposed with relation to the axis of the guide as to pare the wood and substantially preserve the lead, said container having openings within and registering with the ends of said guide.

110

2. A device of the character set forth, comprising a pair of box-form container-members having telescopic relation, and a pencil-guide extending between the flanges of one of said members and having its ends registering with openings in said flanges, said pencil-guide having a taper portion equipped with a knife so disposed with relation to the axis of the guide as to pare the wood and substantially preserve the lead.

120

3. A device of the character set forth, comprising a pair of telescopically-related box-form members having pivotal connections near one end, and a pencil-guide disposed between the lateral flanges of one of said members and having its ends register-

125

130

ing with openings in said flanges, said pencil-guide having a taper portion equipped with a knife.

4. A device of the character set forth, comprising a pair of telescopically-related box-form members, one of which is larger than and receives the other, pivotal connections between said members near one end thereof, and a pencil-guide extending between 10 the lateral flanges of said cover and having

its ends registering with perforations in said flanges, said pencil-guide having a taper portion equipped with a knife so disposed with relation to the axis of the guide as to pare the wood and substantially preserve 15 the lead.

JAMES H. BOYE.

In presence of—
O. C. AVISUS,
F. E. KAYLOR.
